[57] CLAIM

The ornamental design for a room deodorizer dispenser, as shown and described.

DESCRIPTION

FIG. 1 is a perspective view of a room deodorizer dispenser showing my new design;
FIG. 2 is a top plan view thereof, showing the dispenser in an open position;
FIG. 3 is a front elevational view of FIG. 2;
FIG. 4 is a side elevational view thereof, the opposite end being the same as the end shown;
FIG. 5 is a rear elevational view of FIG. 2; and
FIG. 6 is a bottom plan view thereof.

FIG. 1

FIG. 2

FIG. 3

FIG. 4

FIG. 5

FIG. 6
